UNITED STATES PATENT OFFICE

SAMUEL WECHSLER, OF CLEVELAND, OHIO, ASSIGNOR OF ONE-HALF TO THE JAITE COMPANY, OF JAITE, OHIO, A CORPORATION OF OHIO

SEWING MACHINE

Application filed January 17, 1927. Serial No. 161,560.

My invention relates to sewing machines, and more particularly to sewing machines operated in pairs or which produce a plurality of parallel lines of stitches simultaneously in the goods or in which the article being sewn must be fed evenly at two places without bind or interruption to avoid breakage of the thread or needle. For example, in certain types of bags used for shipping cement or other powdered materials, the bags are made of several plies of paper, or paper reinforced with fabric, and the opposite ends of the bag are sewed shut except at one corner where a valve is produced therein to permit the bag to be filled. The paper used is generally of a heavy grade or quality and the many folds and plies make a stiff bag which is difficult to sew under certain conditions. In other words it has been difficult heretofore to sew both ends of the bag shut in one operation using two sewing machines operating in unison. The chief trouble experienced is in the breaking of the thread or needle, due largely to an uneven or interrupted feed of the bag through both machines. Guides are required to keep the opposite ends of the bag in proper alignment with the two sets of needles and feeding devices, but the stiffness of the bag, the nature of the materials, and slight differences in the placement of the plies or in the length of the bags, causes the opposite ends of the bag to feed irregularly or to bind and clutch the guides with objectionable result at one or both needles. A separate strip of binding material is also folded around each end edge of the bag and sewed thereto by the same needles and threads, and the devices which fold these strips also serve to guide the bag to the needles. Accordingly my main object is to provide simple and effective means for hemming or folding separate binding strips and guiding both ends of the bag to the needles without producing any malfunction in sewing operations at either end of the bag, all as hereinafter shown and described and more concisely pointed out in the claims.

In the accompanying drawings, Fig. 1 is a top view on a reduced scale of a sewing machine embodying my improvement, and Fig.

2 is a sectional view longitudinally and vertically thereof. Fig. 3 is an enlarged sectional view of one end of a paper bag which has been hemmed and sewed. Fig. 4 is a plan view, enlarged, of one of the folding and guiding devices, and Fig. 5 is an edge view thereof. Fig. 6 is a cross section of the folding and guiding device on line 6-6 of Fig. 4. Figs. 7, 8, 9, 10, and 11, are cross sections of the pivoted folding member on lines 7-7, 8-8, 9-9, 10-10, and 11-11, respectively, of Fig. 4. Fig. 12 is a sectional view of the device on a large scale taken on line 12-12 of Fig. 4, and showing a binding strip folded around one end edge of a bag as these parts appear just before being sewed together.

The invention comprises two sewing machines A—A mounted oppositely in spaced relation within or upon a flat table 2 and between which a bag B or other article to be stitched may be fed on a straight line by means of a pair of guide members C—C. Two rolls D—D of binding tape are rotatably supported upon a pair of spindle 3—3 in front of the machines A—A where the tape or strip, either of paper or fabric, may be fed around idler rollers 4—4 on straight parallel lines direct to guide members C—C. These members are also particularly constructed to fold the strips into U-shape around the end edges of bag B as the bag is fed into said guide members and passes beneath the respective heads of the sewing machines. As shown, a space or recess 5 is provided centrally at the front of table 2 where the operator may conveniently handle and place the bags between the binding strips and guide members. The bags are made of several plies or layers of paper folded according to usual practices into the form of a flat tube. The open ends of this tube are stitched together or sewn shut on straight parallel lines in passing the bag under the heads of the two sewing machines A—A, and the stitches 6 pass through the overlapping folds 7 of the U-shaped binding strip D as delineated in Fig. 3. Each binding strip D is gradually folded into the desired U-shape as it is drawn lengthwise around the out-

side of guide member C which comprises a flat horizontal base flange 9 and a vertical flange 10 extending at right angles to the base flange but only at the front end thereof. 5 Beyond that point flange 10 is bent at an inclination inwardly over base flange 9 and thence gradually rounded and bent until it is parallel with the base flange to provide a deep horizontal channel 11 for the bag. A 10 U-shaped extension 12 having reverted flanges 14-14 is rigidly affixed to the discharge end of each channel member C, and the space between the two flanges 14-14 forms a continuation of channel 11 through 15 which the bag may pass, while the U-shaped space 13 within extension 12 has a flaring entrance to receive and guide the binding strip. The bag and strip are guided independently of each other, that is, they do not 20 come into contact while passing through the guide member and its extension, and therefore, one does not restrain the other or become pinched while being guided. Extension 12 promotes placement and alignment 25 of the folds of the binding strip on opposite sides of the bag preliminary to stitching the parts together, and in order that the edges of the bag may move freely through these guides without bind the said guide extensions 12 are 30 free to move laterally, preferably against the yielding pressure of a spring 15. Such yielding guides prevent cramping and restraint of movement of the bag, it being understood that the walls of the bag are quite stiff and 35 are not easily buckled while the bag is passing rapidly through a pair of such guides during simultaneous sewing operations at opposite ends of the bag. However, the said guides and folders are secured to the table 40 in definitely spaced relation for a given size or length of bag in order to promote a straight movement in a fixed path to the two sewing machines. Thus, the front end of each guide member C is pivoted at 17 to the 45 table to permit the opposite end extension 12 to swing laterally, and the movable end is secured to the table top or to the bed plate of the sewing machine by a clip 18 having inturned flanges 19 which slidably confine 50 a laterally-extending plate 20 carried by or attached to one side of extension 12. Clip 18 and plate 20 are bent upright at their outer ends and coiled spring 15 is interposed therebetween. The plate is a rigid part of 55 extension 12 but it is loosely confined between the flanges 19 on clip 18 to permit guide member C to swing freely on its pivot pin 17. Clip 18 has a slotted bottom adapted to receive fastening screws 21, the heads of 60 which are exposed through openings 22 in plate 20 so that screws may be released and tightened and the clip shifted within limits on the table top, thus permitting adjustment of the guide members laterally in respect to 65 the edges of the bag or to effect a change

in degree of compression of the spring. The said adjustment, and the mounting of the guide members and tape folders on the table for yieldable lateral movement, may be accomplished in several ways, and therefore, I 70 do not wish to limit myself to the specific structure herein shown and described, but reserve the right to such mechanical modifications thereof as I may be entitled to enjoy in view of the prior art. A detailed 75 description of the sewing machines is also omitted as such machines and their sewing and feeding mechanism are well known to those skilled in the art. A pair of such machines may have their movements synchronized or driven in unison from a single 80 countershaft 23, and when the sewing operation on a given bag is finished the strips of binding tape which connect this bag with the bag sewn in the previous operation, are 85 cut to separate the bags, and the operation is completed. The binding strip or tape is shown in the drawings as a separate piece, but the folding thereof in the guide members corresponds to a hemming operation, 90 and where a bag is particularly constructed to be hemmed in lieu of attaching a separate binder the guide members C-C may also be used for that purpose. 95

What I claim, is:

1. In a double-headed sewing machine of the character described, the combination of two sewing appliances arranged in spaced relation, a pair of correspondingly spaced folders, automatically operating means for varying the distance between said folders during the sewing-induced passage between said folders of articles of unequal dimension measured cross-wise of their direction of movement and means for operating said sewing appliances. 100

2. In a double-headed sewing machine of the character described, duplex sewing appliances arranged in spaced relation, a pair of correspondingly spaced folders mounted 110 for movement toward and away from each other and ahead of said sewing appliances with reference to the direction of intended travel of an article to be operated upon, springs arranged to resist the separating movement of said folders toward positions a greater distance apart than the needles on said double head and mechanism for sewing laminated edges of articles and for drawing them forward. 115

3. In a double-headed sewing machine, the combination for sewing opposite edges of articles likely to vary in width, comprising a support, a pair of folders spaced apart to correspond with the needles on the double head, and mechanism yieldingly connecting said folders with said support and adapted to permit them automatically to approach or recede from each other bodily according to any unforeseen variation in crosswise dimen- 125 130

sions of material being drawn therebetween.

4. In a double-headed sewing machine, the combination for sewing opposite ends of articles likely to vary in length, comprising a support, a pair of guides pivoted on said support and substantially defining the distance between needles of the double head, a pair of folders alined with said guides respectively, and located between them and the needles, and mechanism yieldingly connecting said folders with said support whereby to permit them automatically to approach or recede from each other according to any change of length of the article being drawn therebetween.

15. 5. In a double-headed sewing machine, the combination for sewing opposite ends of articles likely to vary in length, comprising a pair of supports in spaced relation, a pair of folders substantially defining the distance between needles of the double head, a pair of guides alined and connected with said folders, said folders being located between said guides and the needles and mechanism yieldingly connecting said folders with said supports respectively.

6. In a double-headed sewing machine, the combination for sewing opposite ends of articles likely to vary in length, comprising a pair of supports definitely spaced substantially the distance between needles of the double head, a pair of folders located at the near sides of and yieldingly connected with said supports for movement toward and away from each other, said folders being adapted constantly and automatically to approach or recede from each other according to any change of length of the article being drawn therebetween by the sewing operation.

40. In testimony whereof I affix my signature.
SAMUEL WECHSLER.
